CLAIM

The ornamental design for a stowed reading light, as shown and described.

DESCRIPTION

FIG. 1 is a perspective view of a stowed reading light according to one implementation;

FIG. 2 is a top plan view of the stowed reading light of FIG. 1;

FIG. 3 is a front elevation view of the stowed reading light of FIG. 1;

FIG. 4 is a bottom plan view of the stowed reading light of FIG. 1;

FIG. 5 is a back elevation view of the stowed reading light of FIG. 1;

FIG. 6 is a left side elevation view of the stowed reading light of FIG. 1; and,

FIG. 7 is a right side elevation view of the stowed reading light of FIG. 1.

The portions shown in broken lines form no part of the claimed design.

1 Claim, 2 Drawing Sheets
